ABSTRACT

A single float of relatively rigid, buoyant material which is of a length corresponding approximately to the combined lengths of a torso and legs of a user's body has a head support projecting longitudinally from one end thereof, leg supports projecting laterally from the other end thereof, and a strap for holding the mid-section of the user to the underside of the float. The float is also preferably provided with buoyant, swayed-back, stabilizing portions projecting from opposite sides to oppose capsizing of the float.

FIG. 1

FIG. 2

UNITARY BODY FLOAT

BACKGROUND OF THE INVENTION

Many efforts have hitherto been put forth to provide body floats to be used by persons for various purposes, e.g., as life preservers, swim-aid or instruction devices, or for recreational purposes.

Some such devices, as absolute essentials, have had one or more straps for attaching a float or floats to different parts of a user's body, or attaching loops positioned between a user's legs, or pockets or special deformations for receiving the neck, head, arms, or feet of the user.

In the field of recreational uses, prior patents have suggested sail propulsion of such body floats, but have lacked adequate anti-capsizing means or have called for multiple floats rather than a single float.

One of the more recent developments in body floats is disclosed in my U.S. Pat. No. 3,771,181 dated Nov. 13, 1973. The arrangement shown therein involves the use of three separate floats; and where a sail is employed as therein suggested, the user suitably moves his arms and hands to oppose capsizing.

OBJECTS OF THE PRESENT INVENTION

The principal object is the provision of a single body float with head rest and leg rest means aiding in maintaining a proper association of the float with the user's body.

Another important object is the combining of sail means with a single float having adequate, integral means for preventing capsizing.

Another important object is the provision of such head supporting means, associated with the float, as to enable the user easily to view the water surface area toward which the float is traveling.

Other important objects will appear from the following description of this invention.

BRIEF DESCRIPTION OF THE DRAWING

FIG. 1 is a plan view of a body float device according to a preferred embodiment of this invention; and

FIG. 2 is a side elevational view thereof.

DETAILED DESCRIPTION OF THE INVENTION

The illustrated body float device comprises chiefly a float 10 of relatively rigid, multicellular, buoyant material such as, for example, polystyrene, head supporting means 12 projecting from the back end of the float, and laterally extending leg supporting means 14 located adjacent to the float's front end.

The float 10 is illustrated as being elongate; broadest at its aft section 10a and narrowest at its forward section 10b, these two sections tapering from the aft end of the float to the latter's prow 10c which is rounded from its top surface to its bottom surface as at 10d to minimize water resistance to forward motion of the device.

The float 10 is of substantially uniform thickness throughout its length and width. Integral with the float 10 are similar, laterally projecting, stabilizing members 16 which serve as anti-capsizing means, particularly when the float is used with a sail as hereinafter explained.

The stabilizing members 16 preferably have their top surfaces at the same plane as the top surface as the remainder of the float. To minimize water resistance dur-

ing forward movement of the device, the stabilizing members are in a swayed back form as shown in FIG. 1, said members are thinner than the remainder of the float with their undersides at a higher plane than the bottom of the float, and the leading edges of the stabilizing members are rounded downwardly and rearwardly as shown at 16a in FIG. 2.

The illustrated float 10 is provided with a relatively rigid reinforcing frame 18 fixed thereto and, preferably, embedded therein. This frame may be formed of tubing of very light material, e.g., aluminum, which may be circular, square, or of other suitable shape in cross section. The principal member of the reinforcing frame 18 is a trunk 18a which extends throughout the greater part of the float's length. The reinforcing frame 18 also includes rigidly integral reinforcing arms 18b which project laterally of the frame's trunk, throughout the greater part of the lengths of the stabilizing members 16.

20 The head supporting means 12 comprise a relatively rigid, approximately rectangular frame having similar side members 12a, a rear, transverse member 12b, a forwardly disposed transverse member 12c, and a transverse bracing and positioning member 12d. Adjacent to the rear member 12b and spanning between the two side members 12a is a head rest 12e, preferably of some soft material as, for example, tensioned canvas.

The transverse member 12c extends through the float 10a and, preferably, through a rear end portion of the reinforcing frame's trunk 18a, thus being capable of serving as a pivot member enabling the entire head supporting means 12 to be pivotally adjusted upwardly if desired. The positioning member 12d overlies the aft end of the float 10 and serves to hold the head supporting means 12 at its height indicated in FIG. 2. Although the member 12d may be rigidly associated with the head supporting means 12 as a part thereof, as illustrated, it may nevertheless be so separably or adjustably associated therewith as to be readily adjustable or removable to enable the means 12 to be pivoted forwardly, either over or under the float 10, to somewhat reduce the overall length of the device for facility in transporting it to and from the body of water whereon it is to be used.

40 The leg supporting means 14 comprise rigid bars 14a projecting horizontally from opposite sides of the reinforcing frame's trunk 18a adjacent to the latter's forward end and from the float's forward section 10b.

50 THE MANNER OF USING THE DEVICE WITHOUT A SAIL

As thus far detailed, the disclosed device lacks any included propulsion means, and it may be utilized in that limited condition for recreational or other suitable purposes. As thus used, the user's head rests upon the head rest 12e, his neck and the upper part of his chest extend downwardly through an open area 20 circumscribed by the various members of the head supporting means 12, his midsection lies directly underneath the float's aft section 10a, and his legs extend upwardly and forwardly of the stabilizing members 16, straddling the float's forward section 10b and being restfully held in that position by resting at or near his heels, upon the supporting bars 14a.

60 Although the buoyancy of the user's body tends to maintain its relation to the float as set forth in the next preceding paragraph hereof, a belt 22, extending

through a transverse slot 24 formed in the float's aft section 10a, may be buckled about the user's mid-section to hold him securely to the float.

When the device is used without any included propulsion means as just described, the user may propel himself and the float and may steer by the use of his arms and hands much as he would do if he were independently swimming while on his back.

The fact that the head supporting frame is freely pivotable upwardly facilitates the user's disposition of his body as shown in FIG. 2. With said head supporting frame pivoted fully upwardly, the user, standing in the water at the back end of the float 10 may easily first pivot that frame over his head and downwardly; then, with his head on the head rest 12e, he can easily swing his legs upwardly and rest them upon the supporting bars 14a.

It may be noted that, when the user is positioned as in FIG. 2, his head is sufficiently elevated that he may see beyond the float's prow 10c when the float is being propelled forwardly; thus being able to avoid collision with other objects. Also, with some advantage for accommodating the user's body, the aft end of the float 10 may be curved forwardly as at 26 in FIG. 1, and may be beveled downwardly and forwardly as at 28 in FIG. 2.

THE DEVICE IS WELL SUITED FOR USE WITH A SAIL

Beyond what has already been detailed herein, the body float of this invention may include propulsion means in the form of a sail 30, suitably carried upon a mast 32 seated at its lower end in a socket 34 formed in an enlargement 36 of the forward end of the reinforcing frametrunk frame's a. A rope or cord 38, connected between the sail and an eye-bolt 40 threaded into the reinforcing frame's trunk 18a, is provided to enable the user to manipulate the sail to derive the best propulsion results from available wind currents. Any tendency of the float to capsize from the force of laterally directed wind currents is strongly opposed by the stabilizing members 16.

I claim:

1. A unitary body float device comprising a single, elongate, relatively flat, rigid, float member of a length approximating the combined lengths of a user's legs and torso, a head support connected to the float member adjacent to the latter's aft end and extending rearwardly and approximately coplanarly therefrom, rigid, leg supporting members extending laterally from the float member adjacent to the latter's forward end, a pair of rigid side members connecting opposite sides of said head support to opposite sides of a rear area of said float member and defining, between said side members and between said head support and said float member, an open area at the rear end of the float member for accommodating therein the user's neck and adjacent chest portions, a belt extending partially about said float member in position to engage the back of the user's body to hold said body close to the underside of the float member toward the latter's rearward end and to facilitate the raising and resting of the user's feet upon said leg supporting members, and said float member's forward section being sufficiently narrow to permit straddling thereof by the user's legs.

2. A unitary body float device according to claim 1, said float member including an integral pair of oppositely disposed, laterally extending stabilizing members, extending approximately coplanarly with said float member and disposed forwardly of said belt; and said float member, further, including a reinforcing frame embedded therein; said reinforcing frame including an elongate trunk extending longitudinally throughout the greater part of the length of said float member, and including also rigid arms, rigidly connected to said trunk and extending laterally throughout the greater part of the lateral dimension of each of said stabilizing members; whereby said reinforcing frame's trunk and arms materially reinforce the float member and its said stabilizing members.

3. A unitary body float device according to claim 2, said stabilizing members being buoyant and also being swept back with their front edges rounded downwardly and rearwardly to minimize water resistance during forward movement of the device in the water.
